HENRI JEAN JOSEPH MARIE DE REGNAULD DE BELLESCIZE, OF PARIS, FRANCE, AS
SIGNOR TO COMPAGNIE GENERALE DE TELEGRAPHIE SANS FIL, OF PARIS, FRANCE,
A JOINT-STOCK COMPANY OF FRANCE

RECEIVING APPARATUS

Application filed July 7, 1928, Serial No. 290,972, and in France July 13, 1927.

Two methods are known whereby the frequency of a signal may be altered in the receiver apparatus by the aid of a locally generated wave.

5 The first method known in the prior art consists in causing the two oscillations to interfere by superposing them in one and the same circuit by controlling an electrode of a vacuum tube or some other convenient device 10 operating as a detector. The other method consists in causing these two oscillations to act upon different electrodes, and this results in modulating one of these oscillations by the other oscillation.

15 In accordance with the present invention as illustrated in Figs. 1 and 2, it is possible to combine these two methods and thus increase to a considerable degree the amplitude of the oscillation of mean frequency produced in the receiver, the mean frequency being the inaudible intermediate frequency obtained by lowering the incoming signal frequency.

The invention is more clearly understood 25 by reference to the drawing, wherein Fig. 1 represents the circuit arrangement for one form of the invention, Fig. 2 represents the circuit arrangement for a modification wherein a self regenerative tube is used and Fig. 30 2a is a circuit analysis of the arrangement of Fig. 1.

As shown in Fig. 1, the signal is picked up by a resonator 1 consisting, for instance, of a coil antenna or frame tuned to the pulsation 35 ω_1 , and it actuates one of the grids, say 7, confined within a two-grid tube, while the other grid 6 is subjected to the oscillations created by the local generator or heterodyne 2 tuned to wave-length ω_2 . This arrangement results 40 in a current having a mean frequency of $\omega_1 - \omega_2$ or $\omega_2 - \omega_1$, depending on whether ω_2 is smaller or larger than ω_1 . Upon this modulation method the beat method is superposed as follows: The grid 7 upon which the signal 45 is brought to act is connected with the rotor plate 11 of a double condenser, the two stator plates 12 and 13 of which are respectively united with two points 9 and 10 of the local generator or heterodyne and are of opposite polarity. If $H \sin (\omega_2 t + \psi)$ denotes the po-

tential of the plate 12, that of the plate 13 will consequently be $H \sin (\omega_2 t + \psi + \pi)$. The couplings 11-12 and 11-13 cause an electromotive force due to the local generator to be applied to the resonator 1, and as a result 55 there is set up in this resonator an auxiliary current having frequency ω_2 which is superposed upon the signal current and is brought to interfere with it, the two acting 60 combinedly upon the same electrode 7. Hence, the two frequency changing methods are employed at the same time.

But their actions may either neutralize or reinforce each other. Apart from the fact that the electromotive force set up by the 65 local generator 2 in the resonator 1 may be reversed according to whether one of the couplings 11-12 or 11-13 is used, the auxiliary oscillation due to this electromotive force may be displaced in phase either by 70

$$+\frac{\pi}{2} \text{ or } -\frac{\pi}{2}$$

according to whether the heterodyne is tuned 75 to a wave-length below the wave-length of the signal ($\omega_2 < \omega_1$) or above the same ($\omega_2 > \omega_1$).

Hence, four combinations are realizable, to wit:

$\omega_1 > \omega_2$ with coupling 11-12

$\omega_1 < \omega_2$ with coupling 11-12

$\omega_1 > \omega_2$ with coupling 11-13

$\omega_1 < \omega_2$ with coupling 11-13

80

85

The foregoing conclusions may be deduced from the following theoretical considerations. With regard to the high frequency, the terminals of the condenser, shunting the plate battery (Fig. 2), have practically the same potential; taking it as the original one, it can be stated that:

$S \sin \omega_1 t$ = the signal potential at the grid 7.
 $h \sin (\omega_2 t + \psi)$ = the potential produced by 95 the heterodyne at the plate 8.

The direction of the circulation of the heterodyne current in the coils 1₁ and 1₂ being given, the potential produced by the heterodyne at the second grid 6 has approxi- 100

mately the value (the condenser 10, installed for the mean frequency, acting almost like a short-circuit for the high frequency):

$$H \sin (\omega_2 t + \psi + \pi).$$

3 It will be recalled in the first place that the invention has as its sole object to superpose two modulation systems and to amplify one by the other.

10 The first modulation system is the one which may be observed in a tube in which two electrodes are simultaneously submitted to two oscillations; there is obtained a known plate current in which figures, amongst other things, the product of the two oscillations.

15 Here, one of them is the signal, the other the heterodyne. The result is:

$$S \sin \omega_1 t + H \sin (\omega_2 t + \psi) =$$

$$20 \quad \frac{HS}{2} \{ \cos [(\omega_2 - \omega_1) t + \psi] - \cos [(\omega_1 + \omega_2) t + \psi] \}$$

The term

$$25 \quad \frac{HS}{2} \cos [(\omega_2 - \omega_1) t + \psi]$$

represents the first current of modulation which is utilized in the receiver.

20 The second modulation is obtained by superposing, in the usual manner, the oscillations of the signal and the heterodyne on a same electrode and by detecting the resulting oscillation.

25 The grid 7 is already the seat, with respect to the signal, of the oscillation

$$S \sin \omega_1 t$$

40 On it is superposed the one of the heterodyne by means of the electrostatic coupling of one of the condensers 11, 12 or 11, 13 but the sign of the coupling is not arbitrary, the second modulation thus obtained reinforcing the first in one operating sense and choking the same in the other sense.

45 In fact, if C_1 designates the coupling capacity (11, 12 or 11—13) between the heterodyne and the circuit 1, and v the potential of the heterodyne excitation, (which is expressed by

$$50 \quad v = H \sin (\omega_2 t + \psi), \text{ or } v = H \sin (\omega_2 t + \psi + \pi),$$

according to whether the grid 7 is electrostatically coupled with the plate 8 or the other grid 6), then the potential produced by the heterodyne at the top of the resonator 1 (LC), in other words at the grid (7), may be found according to the analysis in Fig. 2a in which I put:

$$LC_1 v'' = L (C + C_1) u'' + u$$

60 In the calculation leading to this result there is implicitly made an approximation, namely that the electrostatic coupling C_1 , produced between the resonator 1 and the heterodyne resonator, will not appreciably modify the voltage v of this latter. This is a legitimate

assumption since the coupling is extremely loose and the two resonators are distinctly out of tune. C_1 is always very small with respect to C ; while the heterodyne has as pulsation ω_2 , the resonator 1 has the pulsation ω_1 of the signal:

$$70 \quad LC\omega_1^2 = 1.$$

This stated, if $\omega_2 > \omega_1$,

$$L(C + C_1)\omega_2^2 = \frac{C_1 + C}{C} \left(\frac{\omega_2^2}{\omega_1^2} \right)^2$$

will be greater than 1; u is a phase with v . On the other hand, for $\omega_2 < \omega_1$, u is in opposition to v .

In the application the oscillations of the current have been assumed as produced in the resonator 1 by the heterodyne; the current being, as known, at 90° with respect to the potential, u will be displaced by

$$\frac{+ \pi}{2}$$

with respect to the potential v .

Accordingly, there exist four possible combinations:

(a) C_1 corresponds to an electrostatic coupling 11, 13; $\omega_2 > \omega_1$. Under these conditions:

$$v = H \sin (\omega_2 t + \psi)$$

$$u = U \sin (\omega_2 t + \psi)$$

(b) C_1 corresponds to a coupling 11, 13; $\omega_2 < \omega_1$ then

$$v = H \sin (\omega_2 t + \psi)$$

$$u = U \sin (\omega_2 t + \psi + \pi)$$

(c) C_1 corresponds to a coupling 11, 12; $\omega_2 > \omega_1$ then

$$v = H \sin (\omega_2 t + \psi + \pi)$$

$$u = U \sin (\omega_2 t + \psi + \pi)$$

(d) C_1 corresponds to a coupling 11, 12; $\omega_2 < \omega_1$ then

$$v = H \sin (\omega_2 t + \psi + \pi)$$

$$u = U \sin (\omega_2 t + \psi + \pi + \pi)$$

$$= U \sin (\omega_2 t + \psi)$$

The sum of the oscillations (signal plus heterodyne) superposed in this manner on the grid 7 has, therefore, the value:

$$S \sin \omega_1 t + U \sin (\omega_2 t + \psi)$$

with the combinations a and d

$$S \sin \omega_1 t + U \sin (\omega_2 t + \psi + \pi)$$

with the combinations b and c .

Considering the extreme smallness which the term S always has in practice with respect to the term U , the amplitude of the resulting oscillation R has very closely the value:

$$U + S \cos [(\omega_2 - \omega_1) t + \psi]$$

with the combinations *a* and *d*

$$U + S \cos [(\omega_2 - \omega_1)t + \psi + \pi]$$

with the combinations *b* and *c* and the current detected due to the second system of modulation has the value

$$KS \cos [(\omega_2 - \omega_1)t + \psi]$$

with the combinations *a* and *d*

$$KS \cos [(\omega_2 - \omega_1)t + \psi + \pi]$$

with the combinations *b* and *c*. The coefficient *K* depends on the detecting power of the tube, which power itself is a function of the degree of action of the heterodyne, hence of the electrostatic coupling *C*, due to condenser 11, 13 or 11, 12.

As a definitive result it may be seen that:

The combinations *a* and *d* furnish a second current modulated in phase with the first. Hence, there exists amplification of the reception.

The combinations *b* and *c* furnish two modulated currents in opposition, with the close approximations made in the calculation. Experience shows that these approximations correspond well to the actuality for the reason that when adjusting the electrostatic coupling (that is the coefficient called *K* in the calculation), the two modulations will destroy each other and the signal disappears on one of the two beats or surges.

Two thereof are favorable, the processes of frequency change coming to reinforce each other, while two are unfavorable. For instance, if it is desired to tune the heterodyne to a wave-length below the signal ($\omega_2 < \omega_1$), the two processes reinforce each other by bringing the plate 11 closer to the plate 13. Hence, reception or signal strength is increased, while the reception is practically suppressed by the coupling 11-12. The opposite condition holds true for $\omega_1 > \omega_2$.

Fig. 2 shows a similar circuit scheme comprising the use of a self-regenerative two-grid tube. The plate 13 may then be associated either directly with the end 10 of the local generator or else with the plate 8, these two points being practically at the same high frequency potential.

It is to be understood, of course, that other schemes than those hereinbefore cited by way of example could be conceived without departing from the spirit of the invention.

What I claim is:

1. The method of receiving electric signals comprising impressing the received signal on one of the grids of a vacuum tube, impressing locally generated oscillations upon another grid of the same vacuum tube, impressing the locally generated oscillations upon the first grid at the same time that the received signal is impressed thereon, and collecting the combined signal and local oscillations in the output circuit of the tube.

2. The method of receiving electric signals comprising heterodyning the received signals with local oscillations and at the same time modulating the received signals by the heterodyning oscillations.

3. A circuit arrangement comprising a resonator for receiving incoming signals, a tube comprising two grids, a device for generating local oscillations, means for impressing the local oscillations upon one of the grids, means for impressing the received signals on the same grid, and means for impressing the local oscillations of the said generating device upon the second grid so that the received signals are heterodyned and modulated at the same time.

4. A circuit arrangement comprising means for receiving incoming signals, a vacuum tube having at least two grids, means for generating local oscillations, the received signals being impressed upon one of the grids and the local oscillations being impressed upon the other grid and upon the plate, a condenser comprising one rotor and two independent stators, the rotor of the condenser being connected to the same grid which receives the incoming signals, the stators being respectively connected to the other grid and the plate, and means to collect the combined oscillations in the anode circuit of the tube.

5. The method of receiving electric signals which consists in impressing received signals upon the control electrode of a space discharge device, generating local oscillations, impressing the generated oscillations upon an independent control electrode of said discharge device and simultaneously impressing the generated oscillations upon the first control electrode with the impression of the received signals thereon.
